UNITED STATES PATENT OFFICE

168,291

METAL CANISTER OR SIMILAR ARTICLE

Freda Diamond, New York, N. Y., assignor to
Continental Can Company, Inc., New York,
N. Y., a corporation of New York

Application April 7, 1952, Serial No. 19,227

Term of patent 3½ years

(Cl. D58—17)

To all whom it may concern:

Be it known that I, Freda Diamond, a citizen of the United States, residing at New York city, State of New York, have invented a new, original, and ornamental Design for Metal Canisters or Similar Articles, of which the following is a specification, reference being had to the accompanying drawing, forming a part hereof.

Fig. 1 is a perspective view of a metal canister, showing my new design;

Figs. 2, 3 and 4 are each perspective views of the other sides thereof.

I claim:

The ornamental design for a metal canister or similar article, as shown.

FREDA DIAMOND.
